BY *John A. Raismith*

ATTORNEY

UNITED STATES PATENT OFFICE.

JOHN E. SPRINGER, OF PALO ALTO, CALIFORNIA.

FOLDING TABLE.

1,369,943.

Specification of Letters Patent.

Patented Mar. 1, 1921.

Application filed February 5, 1920. Serial No. 356,550.

To all whom it may concern:

Be it known that I, JOHN E. SPRINGER, a citizen of the United States, and resident of Palo Alto, in the county of Santa Clara and State of California, have invented certain new and useful Improvements in Folding Tables, of which the following is a specification.

My invention relates particularly to a light collapsible table for camping and other purposes, and it is the object of my invention to provide a table of the character indicated that can be quickly and easily extended for use or folded for transportation, that will occupy but a small space when folded, and that will be cheap to manufacture and highly efficient in its practical application.

In the drawing:

20 Figure 1 is a perspective view of my improved folding table.

Fig. 2 is a perspective detail view of a portion of the table illustrating the corner construction thereof.

25 Fig. 3 is a left side elevation of the table shown in Fig. 1 when partly folded.

Fig. 4 is a right end elevation of the partly folded table shown in Fig. 3.

Referring more particularly to the drawing, 1-1 indicates the two side bars of the table pivoted directly to the rear legs 2-2 as shown at 3-3 pivoted to the front legs 4-4 by means of arms 5-5, the latter being fixedly secured to bars 1-1 as shown at 35 6-6. The pivotal connection between arms 5-5 and legs 4-4 are shown at 7-7. The legs 2-2 and 4-4 are held in extended positions with relation to bars 1-1 by means of breakable braces 8-8 and 9-9 respectively.

At 10 and 11 are rear and front connecting members, jointed at 12 and 13 respectively by means of plates 14-15 pivoted to the adjacent ends as at 16-17 so as to permit folding members 10 and 11 downwardly at their middle points. Members 10 and 11 are pivotally connected to the upper ends of legs 2 and 4 respectively by pivots 18-18 and 19-19 as shown and are held in extended positions with relation to legs 2-2 and 4-4 by means of breakable braces 20-20 and 21-21 respectively.

At 22 is shown a table top built up of slats 23 extending from one side of the table to the other and suitably spaced and connected by flexible material such as canvas

so that the same may be rolled up when not in use. On the under side of the two end slats are placed buttons as 24-24 and 25-25, and in the top surface of end members 10 and 11 are placed slotted sockets as at 26-26 and 27-27 so spaced that buttons 24 and 25 may be positioned therein and held against accidental displacement while the table is in use. The heads of buttons 24-25 engage the under side of the narrow portions of sockets 26-27 so as to form a secure lock therein, this locking of the slats to members 10-11 serves to maintain said members in alinement and securely locks the same against breaking at joints 12 and 13.

Assuming that the table is set up and ready for folding. The top 22 is first disengaged from sockets 26-27 by slipping it sidewise a distance, and laid aside. The braces 20-21 are now broken, also the points 12-13, and the two side portions brought together as shown in Figs. 3 and 4. This being done the braces 8 are broken and the legs 2 folded up against sides 1 as shown in dotted lines at 28. Braces 9 are now likewise broken and legs 4 folded up against legs 2 as shown in dotted lines at 29, the location of pivots 7 in arms 5 serving to so space the folded legs 4 from member 1 as to lay in a substantially parallel position with relation thereto.

This folded structure may now be rolled in cover 22 and tied and the whole structure is ready for packing or carrying. The particular advantages of the structure set forth is that it is extremely rigid when properly set up and yet is light and compact when folded. There are no bolts, nuts or screws to be adjusted or marked parts to be matched when the structure is being set up.

It is to be understood of course, that while I have herein shown and described one specific embodiment of my invention I do not wish to be confined to that embodiment alone but to include all changes in form and construction included within the scope of the appended claims.

I claim:

1. A collapsible table including a pair of parallelly disposed integrally formed side members, a leg pivotally connected to each end thereof, collapsible means for holding said legs in extended position with relation thereto, a foldable end member pivotally attached to the upper ends of each corresponding pair of legs, collapsible means for

- holding said legs in extended position with relation thereto, a foldable top supported by said side and end members, and means for locking said top to said end members to prevent folding thereof.
2. A collapsible table including a pair of parallelly disposed side members, a leg pivotally connected to one end of each member to fold over into substantially the same plane therewith, a leg pivotally connected to the other end of each member to fold over into parallel relation thereto but offset a distance therefrom, a collapsible end member pivotally connected to the upper ends of the two first mentioned legs, a collapsible member pivotally connected to the upper ends of the two second mentioned legs, collapsible means for holding said legs in extended position with relation to said side and end members, a top supported by said side and
- 10
- 15
- 20

end members, and means including said top for holding said end members in extended position.

3. A collapsible table including a pair of parallelly disposed side members, a leg pivotally connected to one end of each member to fold over into substantially the same plane therewith, a leg pivotally connected to the other end of each member to fold over into parallel relation thereto but offset a distance therefrom, a collapsible end member pivotally connected to the upper ends of the two first mentioned legs, a collapsible member pivotally connected to the upper ends of the two second mentioned legs, collapsible means for holding said legs in extended position with relation to said side and end members, and a top supported by said side and end members.

JOHN E. SPRINGER.
